UNITED STATES PATENT OFFICE.

HENRY T. GIBBARD, OF HIGHLAND PARK, MICHIGAN.

JACK.

1,379,011.

Specification of Letters Patent. Patented May 24, 1921.

Application filed February 27, 1920. Serial No. 361,794.

To all whom it may concern:

Be it known that I, HENRY T. GIBBARD, a citizen of the United States, residing at Highland Park, in the county of Wayne 5 and State of Michigan, have invented certain new and useful Improvements in Jacks, of which the following is a specification.

This invention relates to jacks, and has for its object a double action jack, that is, 10 a jack which delivers a working stroke on both the up and the down movement of the lever.

Another feature of this invention is an improved arrangement of telescoping screws 15 to increase the lifting range of the jack in proportion to the height of the jack standard. An automatic arrangement for bringing one screw into lifting operation when the other screw has reached the limit of its 20 range of movement is provided. These and other objects will better appear when described in full.

In the drawings,—

Figure 1 is a fragmentary side elevation 25 of the jack showing the operating parts adjacent the handle.

Fig. 2 is a plan view of the jack, part of the jack being shown in cross section on the line 2—2 of Fig. 3.

30 Fig. 3 is a vertical section through the jack.

Fig. 4 is an elevation of the jack housing or standard.

Fig. 5 is an elevation of the same taken 35 at a position 90 degrees removed.

Fig. 6 is a section taken on the line 6—6 of Fig. 3.

Fig. 7 is a section showing an inverted plan view of the nut that is arranged to 40 lift the inner screw.

Fig. 8 is a detail of the ring used in the operation of the keys that couple the lower nut and the driven gear.

Fig. 9 is a collection of detail views showing the two-part pin used to support the dog.

Fig. 10 is a section on the line 10—10 of Fig. 2.

50 *a* designates the housing, which is made of two pressed-steel half sections welded together at their edges and welded to the base *b*. Before these are welded together the stub shafts *c* are passed through perforations in the sides of the sections until the 55 collars *e* strike against the sections. Thereupon the ends *f* are upset and this together

with the collar *e* serves to securely lock the gear-supporting stub shaft to the standard or housing. Each of the gear-supporting shafts *c* is perforated to receive the cotter pin *g* for holding the lever ends and beveled gears *h* on to the shafts and in mesh with the horizontal beveled gear *j*. To the top of the gear *j* is fastened, by screws, a toothed ring *i* adapted to mesh with the teeth *k* of the nut *l* when the nut bears down on the plate.

m designates the inner telescoping screw. *n* designates the outer telescoping screw. The inner telescoping screw is provided with 70 a reduced portion *o* that merges with the threads through the beveled shoulder *q*. The lower end of the inner screw *m* is plain and adapted to slide freely in the interior of the outer screw *n*, which is adapted to 75 guide it. The interior of the outer screw *n* is provided with a pair of key-ways *r* in which are adapted to engage the ends of the pin *s* that passes through the lower end of the inner screw *m*. Hence the inner screw 80 is prevented from turning by the ends of the pin *s* engaging in the key-ways of the outer screw, while the outer screw is provided with a pair of studs *t* that engage in similar key-ways formed by the angles 85 where the two pressed-steel housing flanges meet (see Fig. 6). Consequently when the gear *j* is turned, it first turns the nut *l* which raises the inner screw *m* because this inner screw is held from turning movement, 90 and consequently must either rise or fall depending upon the turning movement of the nut *l*. When the inner screw *m* approaches the limit of its movement, the follower pins *u*, which have been riding on the threads 95 and have been kept spread, drop down upon the reduced portion *o* of the inner screw and allow the collapsible ring *x* to be contracted by the springs *y*, which press in the dogs *w* that engage in the slots *z* in the nut 10 which rests in the hollow space in the hub of the gear *j*. Heretofore this nut has been inactive but now it is coupled up to turn with the gear *j*. Consequently it being in engagement with the threads of the outer 100 sleeve *n*, which is locked from turning movement, the outer sleeve will now begin to lift and strike the bottom of the nut *l* and lift the teeth *k* of the nut out of engagement with the teeth of the ring *i* on the top 110 of the gear *j*. The outer screw now will rise carrying the inner screw and the nut *l*.

with it until the studs *t* strike the contracted inside portion of the housing and stop the movement.

One of the features of my jack is that the screws are working either on the down or up movement of the lever. This is due to the fact that a driving gear *h* is used on each side of the driven beveled gear *j* and on the down movement, for instance, the dog 2 shown in Fig. 1 and shown in Fig. 2, will ride idly over the teeth 3 of the notched hub of the gear, while the dog 4 (Fig. 2) on the opposite side having its lower jaw in engagement with the notches 3 of the opposite notched hub will turn this hub and the beveled gear *j* in a clockwise direction, thereby turning the nut *l* in a similar direction and serving to push the inner screw *m* up. On the up stroke of the lever 5 it will be apparent that the dog 2 will turn the notched hub of the companion beveled gear *h* in a counter-clockwise direction, continuing to rotate the gear *j* in a clockwise direction and hence continuing the lift of the screw *m* or the outer screw *n* (in case the inner screw has reached the limit of its movement and the automatic shift of the lock is operated to key the nut 10 up with the gear *j*.)

The dogs 2 and 4 are simultaneously operated to bring the upper jaw of one and the lower jaw of the other into engagement with the notched hubs, or vice versa, the lower jaw of the one and the upper jaw of the other into engagement with the notched hubs by means of the pivoted yoke 6 that is supported to swing at its center on a trunnion-like extension 7 of the forging 8 that forms the handle part of the lever. The lever is formed by a pair of yoke arms 9 that are bossed at 10 and perforated to fit over the ends of the gear-supporting stub shafts *c* and locked thereon by the cotter pins *g* and which run together at their other ends and are riveted together by the rivets 11 which also pass through the extension of the handle forging 8 and unite the parts together to make the composite lever. The intermediate portion of the yoke arms 9 spreads out into channels, as is indicated in Figs. 1 and 2, and also form a fork 12 in which is adapted to pivot the composite pin 13 (detailed in Fig. 9) that passes through a lost motion opening 20 in the dog 2 or 4 of such shape as to turn the dog with it but allow a limited lost motion to allow the dog enough independent movement to ride over the teeth when not in action. The crank 14 is fitted on to the pin so as to turn the same with the turning of the crank. Each dog is provided with a tail 15 against which the compression spring 16 bears. The spring seats in a pocket 21. It will be seen that the pivot 13, the tail piece 15, and the spring 16 form a toggle which tends to resist movement by its dead center line in a familiar way. Now ob-

viously when the finger piece 17 of the dog-shifting yoke 6 is raised or lowered, it presses the tails of these two dogs one below and one above the dead center line of the toggles. Hence the compression spring tends to keep the dogs in either position they have been brought. Obviously when one dog is in one position the other dog is in the reversed position. They are always set by this yoke so as to be in position to cause either the screws to raise or lower depending upon which action is desired, and are never so that the two gears *h* are locked against each other.

What I claim is:

1. In a jack, the combination of a standard, a pair of telescoping screw lifting members in the standard, a pair of nuts one for actuating each screw, a gear for actuating the nuts one at a time, and means for coupling up the gear to the nuts selectively so that when one screw has reached the limit of its movement the other nut is connected with the gear to actuate the other screw. 80

2. In a jack, the combination of a standard, a pair of telescoping screw lifting members, a pair of nuts for lifting the screws, an actuating member for rotating the nuts, and means for coupling up the actuating member to the other nut when the limit of movement of the first-actuated screw is reached. 90

3. In a jack, the combination of a standard, a pair of telescoping screw lifting members, a pair of nuts one for actuating each screw member, a gear for turning the nuts, and means for automatically connecting the gear with the nut for actuating the second screw when the first screw has reached the limit of its movement. 100

4. In a jack, the combination of a standard, a pair of telescoping screw lifting members, nuts one for operating each screw, a gear for turning the nuts alternately, and means for automatically coupling the gear up to the other nut when the limit of movement of the screw actuated by the first-actuated nut is reached. 110

5. The combination of a standard, a pair of telescoping screws to act as lifting members, a pair of nuts one for actuating each screw, a gear for actuating the nuts, a toothed connection between the gear and one of the nuts, a spring-actuated coupling arrangement between the gear and the other nut, and means for normally holding said spring-actuated coupling out of engagement 120 with the other nut until the inner screw has reached the limit of its movement, the surface of the inner screw being provided with means to release said holding means to allow the spring-actuated coupling members to engage the gear and nut when the inner screw has reached the limit of its movement. 125

6. In a jack, the combination of a standard, a pair of telescoping screw lifters supported therein, a pair of nuts, an upper one 130

- and a lower one, a gear for turning the nuts, a toothed connection between the gear and the upper nut for actuating the inner screw, a plurality of spring-pressed dogs 5 carried on the gear for coupling the gear to the lower nut, a segmental ring, and following pins for engaging the surface of the inner screw to normally hold the spring-pressed dogs out of coupling arrangement 10 with the lower nut, the said inner screw being provided with a reduced end portion adapted to allow the ring and following pins to release the dogs when the limit of movement of the inner screw is reached. 15 7. In a jack, the combination of a standard, a lifting screw supported therein, a gear for actuating the same, a pair of driving gears therefor one on each side of the said driven gear, notched hubs for each 20 driving gear, a yoke-like handle lever adapted to straddle the gears, double jaw dogs on the yoke ends of the handle, a spring in connection with each double jaw dog arranged therewith to be thrown by 25 the center line when the dog is moved to bring one or the other of the jaws in engagement with the notched hub, and a member which can be thrown to bring the one jaw of one dog into engagement with the 30 hub and the opposite jaw of the other dog into engagement with the other notched hub. 8. In a jack, a housing formed of a pair of pressed-steel parts, one part having a 35 gear-supporting shaft introduced from the outside thereof, and an end upset on the inside of the pressed-steel part, the two pressed-steel parts being then welded together at their meeting edges. 40 9. In a jack, the combination of a standard, a gear whose revolution raises or lowers the standard, a pair of gears on the opposite side of the first-mentioned gear for actuating the same, a lever provided with a 45 yoke-like end adapted to straddle the said gears, dogs on the end of the lever for engaging the gears to actuate the same, a dog-actuating device for simultaneously engaging one dog and disengaging the other dog, each connection of said device with the dogs 50 embodying a lost motion arrangement to permit the dogs to ride over the teeth that they engage in their non-active movement. 10. In a jack, the combination of a standard, a lifting member therein, a gear for 55 operating the lifting member, a pair of gears on opposite sides of the first-mentioned gear, a lever provided with a yoke-like end adapted to straddle said gears, dogs pivotally carried on the yoke-like end of 60 said lever, means between the dogs and the yoke-like ends of the lever for maintaining the dogs in their active or inactive position, and a member pivoted on the yoke-like end of the lever for simultaneously throwing 65 one dog out of active relation with its gear and the other dog into active relation with its gear and including a lost motion connection with each dog permitting movement of the dog in riding inactively over the teeth 70 it engages. 11. In a jack, a housing formed of a pair of channels with turned-out flanges, one channel having a gear-supporting shaft introduced from the outside thereof and an end 75 upset on the inside of the channel, the two channels being then secured together along their flanges. 12. In a jack, a housing formed of a pair of channels, one channel having a gear-supporting shaft provided with a collar introduced from the outside thereof, the collar limiting the amount that the shaft may be introduced into the channel, and an end 80 upset on the inside of the channel, the two 85 channels being secured together at their meeting edges.

In testimony whereof I affix my signature.

HENRY T. GIBBARD.
